UNITED STATES PATENT OFFICE.

CARL ARNOLD, OF NUEREMBERG, GERMANY.

SPARK-PRODUCING TOY.

Application filed August 1, 1927, Serial No. 209,881, and in Germany January 31, 1927.

It has become known to produce sparks by means of a cerium stone sliding or rotating on an emery disk, said sparks becoming then visible from the outer side in alternating colors through openings provided in the toy and having several transparent plates. This arrangement is not suitable for toys with transparent disks as too many operations are necessary and the costs of manufacturing of the toy are too high. This inconvenience is avoided, according to the invention, in a simple and cheap manner. The lever carrying the cerium stone and which either rotates or is stationary is extended and openings are arranged in the extension and closed with colored transparent panes fixed by means of flaps. This arrangement is cheap and presents further the advantage that the sparks produced strike very strongly onto the transparent panes as the lever and emery disk are close together, the sparks being atomized by the striking against the colored panes so that a splendid color effect is produced.

In a second form of construction a colored transparent pane is fixed by means of a flap directly on one end of the lever which carries the cerium stone.

Two forms of construction of a lever carrying the cerium stone are shown, by way of example, in the accompanying drawings, in which:—

Fig. 1 is a longitudinal section,
Fig. 2 a top plan view.

Fig. 3 shows in side elevation the lever of the second form of construction.

Fig. 4 shows the improved lever in connection with a spinning top.

On a lever *a* a cerium stone *b* is fixed which is in contact with an emery layer *d* on a disk *c*. The lever *a* is, according to the invention, extended and has in its extended portion one or several openings *f*. On the upper or lower surface of the lever *a* differently colored transparent panes *g* are fixed to close said openings *f*. Flaps *h* of the lever *a* serve to securely hold said transparent panes.

In the second form of construction a flap *i* on one end of the lever *a* serves to securely hold a colored pane *k* when said flap is bent over so that said colored pane *k* projects from the end of the lever and is securely held on the same.

I claim:—

1. In a spark producing toy, in combination with an emery disk a cerium-lever and cerium stones fixed on said lever so that they slide on the emery disk, an extension at one end of said lever and having apertures, flaps at the sides of said extension portion of said lever, and colored transparent panes placed over said openings and securely held in position by the folded over flaps of said lever.

2. In a spark producing toy as specified in claim 1 a flap at the free end of said lever, and a colored transparent pane held on said lever by the folded over flap so that it projects from the end of said lever.

In testimony whereof I affix my signature.

CARL ARNOLD.
